UNITED STATES PATENT OFFICE

142,777

DESIGN FOR A CONTROL KNOB OR SIMILAR ARTICLE

Melville Eastham, Cambridge, Mass., assignor to
General Radio Company, Cambridge, Mass., a
corporation of Massachusetts

Application December 6, 1944, Serial No. 116,746

Term of patent 14 years

(Cl. D26—1)

To all whom it may concern:

Be it known that I, Melville Eastham, a citizen
of the United States of America, residing at Cam-
bridge, in the county of Middlesex and Common-
wealth of Massachusetts, have invented a new,
original, and ornamental Design for a Control
Knob or Similar Article, of which the following
is a specification, reference being had to the ac-
companying drawing, forming a part thereof.

Fig. 1 is a front elevation of a control knob
showing my new design;

Fig. 2 is a side elevation;

Fig. 3 is a bottom plan; and

Fig. 4 is a top plan.

I claim:

The ornamental design for a control knob or
similar article, substantially as shown.

MELVILLE EASTHAM.
